UNITED STATES PATENT OFFICE.

PAUL CZIGLER, OF MURA KIRABY, AUSTRIA-HUNGARY.

SLEEPER FOR RAILWAYS, &c.

SPECIFICATION forming part of Letters Patent No. 642,301, dated January 30, 1900.

Application filed November 28, 1898. Serial No. 697,581. (No model.)

To all whom it may concern:

Be it known that I, PAUL CZIGLER, a subject of the Emperor of Austria-Hungary, residing at Mura Kiraby, in the Empire of Austria-Hungary, have invented certain new and useful Improvements in Sleepers for Railways and the Like, (for which I have applied for patents in Germany, dated October 27, 1898; in Austria, dated November 5, 1898; in Hungary, dated October 23, 1898; in France, dated November 3, 1898; in Belgium, dated November 3, 1898; in Italy, dated November 2, 1898; in Sweden, dated October 31, 1898; in Norway, dated November 3, 1898; in Denmark, dated 15 October 31, 1898, and in Switzerland, dated October 31, 1898,) of which the following is a specification.

The rapid growth of railway traffic and the continuous increase of speed in traveling have 20 so enlarged the claims on the maintenance of the permanent way that such maintenance has ceased to be able to fully answer the requirements. This applies more particularly to the sleepers, ordinarily of wood, which have 25 the great defect that in consequence of the rotting of the wood the sleepers require frequent renewals, which greatly increases the cost of maintenance.

The object of this invention is to substitute 30 for the sleepers hitherto used other devices answering in every respect the present requirements and capable of being easily manufactured, while at the same time surpassing in elasticity and durability the wood and iron 35 sleepers hitherto used and being on account of their extraordinary power capable of bearing the greatest weights or loads.

This new sleeper is produced in a press from a plastic mass which becomes hard and 40 has outwardly a similar shape to that of wooden sleepers, but is hollow inwardly and is strengthened by a wire-netting.

This improved sleeper is shown in the accompanying drawings, wherein—

45 Figure 1 is a vertical longitudinal section of the sleeper. Fig. 2 is a cross-section thereof, and Fig. 3 is a plan view of the same.

The cross-section of the sleeper has the shape of a trapezium, which is more particularly adaptable to consolidate the permanent way. This shape is the same outwardly and inwardly. The hollow part x is provided, at

the parts where the rails a or the chairs b are laid, with web-pieces c . As the walls increase in thickness at the top and toward the center, 55 the hollow part or tubular longitudinal channel x flares toward both ends, so that the web-pieces c can be tightly driven in. The wire-netting, which is placed in the center of the wall thickness, surrounds the hollow part like 60 a culvert and consists of closed arched ribs d , which brace up the sleepers and impart a considerable amount of elasticity thereto. These ribs d are formed with longitudinal wire chains in order to increase the resistance of 65 the sleeper to traction. The chain-wires e are suspended at their ends to the ribs d .

The material of the sleeper consists of a mixture of Portland cement and coarse coal-slag, which can be readily molded in presses 70 and forms, after it is dry, a firm and exceedingly tenacious mass.

The web-pieces c , which are used to receive the rail-spikes f , consist of a peculiar elastic mass composed of asphalt, tar, and 75 river-sand, to which is added a quantity of pig-hair or of other animal hair. A protecting-sheath i of the same elastic mass surrounds the whole of the outer wall of the sleeper for the purpose of protecting the latter and preventing it from being squashed or to protect 80 it from the effects of concussions or of other outwardly injurious damaging influence.

The elastic web parts c are held or fastened on both sides by plugs h , formed of the same 85 material as the sleeper and which, being comparatively stiff or inelastic, prevent the undesirable expansion of the plastic web parts c . The holes g for the spikes extend as far as the web parts c and are bored or drilled in 90 the body of the sleeper before the latter is subjected to pressure, Fig. 3. As already stated, the sleepers herein described are made by presses and are originally hollow throughout.

The wire-netting d is first suspended 95 in the press-mold and is temporarily fixed by means of removable nails, which are withdrawn after the necessary pressure has been exerted in the molds. In the middle of the wire-netting is arranged before compression 100 takes place a core having for its object to form the hollow space x . This core is composed of a number of parts or sections having a cruciform shape and is withdrawn at

both ends after compression from the finished sleeper. After the sleeper has hardened, the web-pieces or plugs *c* are driven in position. The whole mass forms, after petrifying or 5 hardening, a thoroughly tenacious and elastic sleeper wherein no warping can take place, as with wooden sleepers, while owing to the particular manner in which it is manufactured it has a much more regular form than the 10 wooden sleepers hitherto used. The web-pieces *c* hold the driven spikes firmly in consequence of the elasticity of the material and have, moreover, the advantage that after removing the spikes the holes close themselves 15 again, so that a new spike can be driven again in the same place, whereas a spike cannot be driven twice in the same place in wooden sleepers, and hence the latter soon become useless. 20 The wire-netting imparts considerable elasticity and tenacity to the sleeper, so that the latter cannot be possibly torn asunder.

What I claim, and desire to secure by Letters Patent of the United States, is—

1. The combination with a railway-sleeper 25 having a tubular longitudinal channel flaring toward an end of the sleeper, an elastic wedge-shaped supporting-body in the tubular flaring space, and plugs of comparatively stiff material on each side of said elastic supporting- 30 body.

2. A hollow railway-sleeper comprising a metallic skeleton coated externally and internally with a composition containing cement and coarse coal, in combination with filling-pieces in said sleeper containing asphalt, tar, 35 animal-hair and sand.

In testimony whereof I have hereunto set my hand in the presence of two witnesses.

PAUL CZIGLER.
